KATHERINE R. O'KANE, OF PHILADELPHIA, PENNSYLVANIA.

DUPLICATING-MACHINE.

1,070,269.

Specification of Letters Patent. Patented Aug. 12, 1913.

Original application filed April 21, 1913, Serial No. 762,643. Divided and this application filed June 2, 1913. Serial No. 771,200.

To all whom it may concern:

Be it known that I, HERMAN G. LIEBENTHAL, a citizen of the United States, residing at Philadelphia, in the State of Pennsylvania, have invented a certain new and useful Improvement in Duplicating-Machines, whereof the following is a specification, reference being had to the accompanying drawings.

10 My improvement is particularly applicable to printing machines of the type known commercially as the "Multigraph" comprising a rotary printing cylinder having a series of undercut channels in its perimeter extending parallel with its axis to receive complementary shaped flanged type which said cylinder presents in opposition to the other member of the printing couple. As ordinarily constructed, the printed impressions 15 from such a machine are irregular in accordance with the length of the lines of type; because the lines of type extend parallel with the axis of the printing cylinder and are successively pressed between the 20 printing couple with a given pressure which, being the same for each line, is variable per unit of length of the line. For instance, a line one-half the length of the cylinder would be printed with a pressure, per unit 25 of length of that line, double the pressure per unit of length of a line which is the full length of the cylinder, and consequently the shorter the lines the more deeply and darkly 30 they are printed.

35 Therefore, it is the object of my invention to provide such a machine with means to equalize the pressure per unit of area upon the successive lines of type in compensation for variations in the length of the lines; so 40 that the printed impressions made from successive lines shall be uniform in depth and darkness regardless of differences in the length of said lines.

45 My invention provides means interposed between the couple at the short lines to sustain a portion of the printing pressure which would otherwise be concentrated on said short lines, and, as hereinafter described, such devices include detachable cam elements which may be fitted in the type channels in the printing drum, or otherwise applied to the latter, to bear upon a pair of bearing rollers carried by the platen shaft 50 concentric with its axis. For instance, the

duplicating machine which I have chosen 55 for illustration includes the combination with a rotary printing drum; of a platen shaft extending parallel with the axis of said printing drum; an eccentric on said shaft; a platen roller journaled on said eccentric; a pair of bearing rollers carried by said shaft concentric with its axis; clutch means connecting said bearing rollers for rotation with said platen roller; detachable cam members on said printing drum; arranged to bear upon said bearing rollers; including an element having recesses in its periphery extending parallel with the axis of said printing drum, and elements detachably fitted in said recesses to project beyond 65 the printing faces of the printing elements on said drum; and means whereby said shaft may be turned to adjustably vary the distance between the axes of said printing drum and platen, without varying the distance between the axes of said printing 70 drum and bearing rollers; whereby the printing pressure between said drum and platen may be variably predetermined to be 75 different at different regions of the circumference of said drum. Said construction includes the clutch means aforesaid because the platen is positively driven so as to turn synchronously with the printing drum. However, if the bearing rollers are not included 80 in the driving means of the platen, said clutch means may be omitted.

85 My invention comprises the various novel features of construction and arrangement hereinafter more definitely specified.

90 In the drawings; Figure I is a fragmentary vertical longitudinal sectional view of a portion of a Multigraph machine including a convenient form of my invention. Fig. II is a fragmentary transverse sectional view, taken on the line II, II in Fig. I. Fig. III is a fragmentary transverse sectional view, taken on the line III, III in Fig. I. Fig. IV is a fragmentary longitudinal sectional view of a portion of the printing 100 drum shown in Fig. I, but on a larger scale, showing the arrangement of my invention in connection therewith. Fig. V is a fragmentary transverse sectional view of said drum taken on the line V, V in Fig. IV. Fig. VI is a fragmentary transverse sectional view of said drum taken on the line 105 VI, VI in Fig. IV. Fig. VII is a perspec-

5 tive view of one of the detachable cam members shown in Fig. VI. Fig. VIII is a fragmentary transverse sectional view of said drum taken on the line VIII, VIII in Fig. IV. Fig. IX is a fragmentary transverse sectional view of a printing drum similar to Fig. VI but showing a modified form of my invention. Fig. X is an elevation of one of the cam type.

10 In said figures; 65 indicates the frame of a Multigraph machine having bearings 66 and 67 for the shaft 68 of the rotary drum 69 having the curved surface 71 with the undercut channels 72 therein. Said drum 15 69 is provided with means for moving said surface 71 about its center of curvature, including the handle 74 connected with said shaft 68. The platen shaft 75 being journaled in the bearings 77 and 78 in said frame 65, extends parallel with the axis of said printing drum and has the eccentric 20 80 on which is journaled the cylindrical platen roller 81 having the face 82 of resilient material. Said bearing 78 is a rotary eccentric having the lever arm 84 slotted to receive the screw 85 by which it may be secured in adjusted position, so that the distance between the axes of said drum 69 and platen roller shaft 75 may be precisely 25 determined. Said shaft 75 carries the pair of bearing rollers 87 and 88 which are journaled on the respective rotary eccentric bearings 90 and 91 which are rigidly connected by the bar 92, shown in Figs. II and III, so 30 that they may be simultaneously turned on said shaft 75 by the lever arm 96, shown at the left hand side of Fig. I and in Fig. III, having the slot 97 for the screw 98 by which it may be secured in adjusted position, so that the distance between the axes of said drum 69 and said rollers 87 and 88 may be precisely determined, and varied, without changing the position of the axis of said platen roller shaft 75. Said bearing 40 45 rollers 87 and 88 are respectively provided with clutch means connecting them for rotation with said platen roller 81 and including the crown lugs 99 and 100 respectively fitting in the recesses 101 and 103 at the 50 opposite ends of said platen 81. Said drum 69 is provided with the driving gear 105 engaging the platen gear 106 which is supported by said shaft 75 but journaled on the portion 107 of said eccentric 90, which portion is concentric with the axis of said shaft. Clutch means are provided operatively connecting said platen gear 106 with said bearing roller 87 including the crown lugs 109 on said roller 87 fitting the recesses 110 in said platen gear. It is to be understood that the arrangement last above described is such that when said drum 69 is turned to move its surface 71 about its center of curvature, to wit, the axis of said 60 65 shaft 68, said platen 81 is correspondingly

70 moved; said bearing roller 87 serving as a coupling between said platen gear 106 and the platen 81, although said roller and platen are rotatable upon respectively different axes in eccentric relation with each other.

75 It may be observed that the construction above described provides said bearing rollers with means to precisely adjust the distance between their axes and the axis of the printing drum without changing the position of the platen roller shaft upon which said rollers are supported. However, a 80 form of my invention wherein the only means for determining the precise distance between the axes of the printing drum and the bearing rollers are adjustable bearings at the opposite ends of the platen roller shaft upon which said bearing rollers are mounted is claimed in my application Serial #762,643, filed April 21, 1913 for Letters Patent of the United States for improvement in duplicating machines of which this application is a division. Such adjustment is used to vary the printing pressure between the resilient surface 82 of said platen roller 81 and the printing faces of the type 40 which, as shown in Fig. V, have flanges 41 fitting said undercut channels 72 in the curved face 71 of said drum 69. Such variation in the printing pressure is effected to vary the depth of the impression of the printing faces of said type 40 with respect to the paper 42, through the inking ribbon 43 which is interposed between said paper and said faces as shown in Fig. I. In order to equalize the pressure per unit of area upon the successive lines of said printing type 40 in compensation for variations in the length of said lines, I interpose between said curved surface 71 of the drum 69 and the opposed surface 82 of the platen 81 a cam element or elements carried by said drum at its surface 71. Said cam element may be a cam type 45 having flanges 46 fitted to said channels 72 like the printing type 40 but having a bearing face projecting beyond the printing face of said type 40, as shown in Fig. V. Although said type 45 only extends in alinement with one line of type 40; 100 it is to be understood that such cam type may be made to bridge two or more of the lines of said type 40; for instance, as shown in Fig. VIII the cam type 48 extends transversely with respect to five of the channels 105 110 72 and has the flange 49 fitting in each of said channels. However, it is to be understood that such bridge cam type may be made to extend transversely with respect to several of the channels 72 without having 115 flanges 49 engaged with all of them; such flanges in two places on such a bridge cam type being sufficient to hold the latter in adjusted position. As shown at the right hand end of channels 72, such cam type 45 120 125 130

(or 48) may bear directly upon the opposed platen surface 82. However, as above described, said platen surface is resilient and consequently such an arrangement would not 5 positively determine the radial extent of the space between the opposed surfaces of the printing couple. Of course, said platen roller 81 may be provided with rigid zones serving as bearings in opposition to the cam type aforesaid; but such arrangement would 10 limit the longitudinal extent of the platen available for printing purposes, particularly at the right hand end of the channels 72, as indicated in Fig. I. Therefore, it is preferable to locate said cam type 45, etc., at the 15 left hand end of the drum 69, in opposition to the rigid bearing roller 88, as shown in Fig. I, and to provide cam elements arranged to be removably set in opposition to 20 the bearing roller 87 at the right hand end of the drum 69, as shown in Fig. I.

As ordinarily constructed the Multigraph machine has a cylindrical recess 51 at the circumference of the drum 69, at the right hand end thereof, as indicated in Fig. I, and I secure therein a cam device opposed to the bearing roller 87 and including the sectoral cam rack 52 which is rigidly connected with said drum 69, conveniently by screws 53 at 25 the opposite ends of said rack, one of which is indicated in Fig. VI. As shown in Fig. VI said cam rack 52 has recesses 55 which are undercut for engagement with the detachable cam type 56 which are conveniently 30 formed of pressed sheet metal and so proportioned that they project radially with respect to the drum 69 beyond the printing faces of the printing type 40 to the same extent as the cam type 45 and 48 above described. Referring to Fig. VI it may be observed that said recesses 55 are of such circumferential extent as to only leave at the 35 perimeter of the cam rack 52 the circumferentially undercut projections 58 to be embraced by the removable cam type 56. However, it is to be understood that suitable 40 recesses to receive and hold such cam type may be otherwise formed; for instance, as shown in Fig. IX, the recesses 60 which engage the cam type 56 are merely sawcuts in 45 the perimeter of the rack.

It is to be understood that the cam devices including the racks 52 above described are mere expedients to fit the duplicating 55 machines as now on the market, and that a simpler arrangement would be to extend the drum channels 72 in opposition to the bearing roller 87 above described so that the cam type 45 may be set in opposition to said 60 roller like the printing type 40. Moreover, although I prefer to employ bearing rollers in opposition to the cam elements on the printing drum to limit the depth of the printing impression of the printing type, as 65 above described; it is to be understood that

other means may be arranged to coöperate with said cam elements for that purpose.

I do not desire to limit myself to the precise details of construction and arrangement herein set forth, as it is obvious that various 70 modifications may be made therein without departing from the essential features of my invention as defined in the appended claims.

I claim:—

1. In a duplicating machine, the combination with a member having a surface formed to carry rows of type; of a platen coöperating with said surface; means arranged to variably limit the depth of printing impression of said type with respect to said platen, including cams detachably carried at said surface in spaced relation with each other, bearing rollers opposed to said cams, a normally stationary shaft supporting said rollers, having an eccentric bearing for said 80 platen, means whereby said shaft may be adjustably turned, rotary eccentric bearings interposed between said rollers and said shaft, means rigidly connecting said bearings, whereby they may be simultaneously 85 turned on said shaft, including a lever arm; and means whereby said lever arm may be secured in adjusted position.

2. In a duplicating machine, the combination with a member having a surface formed to carry rows of type; of a platen coöperating with said surface; means arranged to variably limit the depth of printing impression of said type with respect to said platen, including cams detachably carried 90 at said surface in spaced relation with each other, bearing rollers opposed to said cams, a shaft supporting said rollers, rotary eccentric bearings interposed between said 95 rollers and said shaft, means rigidly connecting said bearings, whereby they may be simultaneously turned on said shaft, including a lever arm; and means whereby said lever arm may be secured in adjusted 100 position.

3. In a duplicating machine, the combination with a member having a surface formed to carry rows of type; of a platen coöperating with said surface; means arranged to variably limit the depth of printing impression of said type with respect to said platen, including cams detachably carried 105 at said surface in spaced relation with each other, bearing rollers opposed to said cams, a shaft supporting said rollers, and rotary eccentric bearings interposed between said 110 rollers and said shaft.

4. In a duplicating machine, the combination with a member having a surface formed to carry rows of type; of a platen coöperating with said surface; means arranged to limit the depth of printing impression of said type with respect to said platen, including a cam carried at said surface, a bearing roller opposed to said cam, a shaft 120 125

bearing roller opposed to said cam, a shaft 130

supporting said roller, and a rotary eccentric bearing interposed between said roller and said shaft.

5. In a duplicating machine, the combination with a platen; of a member having a surface with a recess in its periphery; a printing type fitted to said recess; a cam type fitted to said recess and having a bearing face projecting beyond the printing face 10 of said other type; and means arranged to coöperate with said cam type to limit the depth of printing impression of said printing type with respect to said platen, including a bearing roller and eccentric bearing 15 means for said roller adjustable toward and away from said surface.

6. In a duplicating machine, the combination with a member having a surface formed to carry rows of type; of a rotary platen co-operating with said surface; means arranged to limit the depth of impression of said type with respect to said platen, including a cam at said surface and a bearing roller adapted to coöperate with said cam; a 20 shaft supporting said platen and bearing roller; means whereby said platen and bearing roller are independently adjustable toward and away from said surface, including relatively rotatable eccentrics on said shaft, 25 respectively supporting said platen and said bearing roller, and levers whereby said eccentrics may be respectively turned; and means whereby said levers may be secured in 30 adjusted position.

7. In a duplicating machine, the combination with a member having a surface formed to carry rows of type; of a rotary platen co-operating with said surface; means arranged to limit the depth of impression of said type with respect to said platen, including a cam at said surface and a bearing roller adapted to coöperate with said cam; a shaft supporting said platen and bearing roller; and means whereby said platen and bearing roller are independently 35 adjustable toward and away from said surface, including relatively rotatable eccentrics on said shaft, respectively supporting said platen and said bearing roller.

8. In a duplicating machine, the combination with a member having a surface formed to carry rows of type; of a platen coöperating with said surface; means arranged to limit the depth of impression of said type with respect to said platen, including a cam at said surface and a bearing roller adapted to coöperate with said cam; a shaft; and means whereby said platen and bearing roller are independently adjustable toward and away from said surface, including relatively rotatable eccentrics on said shaft.

In testimony whereof, I have hereunto signed my name at Philadelphia, Pennsylvania, this 29th day of May, 1913.

HERMAN G. LIEBENTHAL.
